UNITED STATES PATENT OFFICE.

HUGH MOODY RHIND, OF WHEATON, ILLINOIS.

GOLF CLUB.

Application filed June 17, 1918. Serial No. 240,302.

To all whom it may concern:

Be it known that I, HUGH MOODY RHIND, a subject of the King of Great Britain and Ireland, residing at Wheaton, in the county 5 of Du Page and State of Illinois, have invented certain new and useful Improvements in a Golf Club, of which the following is a specification.

My invention is an improved golf club and 10 relates more particularly to the disposition and arrangement of the metal weight customarily added to wooden clubs. Heretofore the requisite addition of weight to wooden clubs has been effected by the addition of 15 metal inserts to the wooden clubs, a common form of construction being that in which the metal is inserted at the rear side of the head of the club about opposite to the striking surface of the face of the club. Among the 20 objects of my invention are the placing of the metal weight at the extreme end of the club most remote from the handle, that is, upon the lower surface of the head of the club, and the proportioning of the weight in 25 such manner that the center of gravity of the head of the club will lie approximately in a plane passing through the axis of the shaft of the club substantially perpendicular to the sole of the club, thus obtaining a per- 30 fect balance of the club whereby it tends to assume, under the influence of gravity, the proper position for impact upon the ball. In securing these objects my invention takes 35 the form of a flat weight secured to the lower surface of the head of the club and extending across the lower surface thereof from the striking face to the rear part of the head, the metal weight being so proportioned as to width and thickness as to bring 40 the center of gravity of the head in approxi- mately the position above referred to. In the preferred form of construction the forward edge of the weight is flush with the 45 striking face of the club and forms the lower part thereof, the weight itself thus constituting a protection and reinforcement for the lower part of the striking face and thereby dispensing with the necessity of using the fiber inserts customarily employed for 50 the protection of the lower part of the striking surface of wooden clubs. My improved weight also serves the purpose of a metal sole for the club, constituting as it does, a metallic protection extending over the 55 greater part of the lower surface thereof. My improved weight, however, is in no sense

simply a metal protecting sole for the club, its primary purpose being that of a weight and its function as a protecting sole being incidental to its location at the extreme end 60 of the club most remote from the handle, where it contributes the maximum of momentum to the club when it is swung to strike the ball. As is well known, the usual metallic protecting sole for wooden clubs 65 consists merely of a thin sheet of metal, generally brass, flanged upwardly at its edges around the lower part of the club head. Such metallic protecting soles do not contribute materially to the weight of the clubs 70 upon which they are mounted and are not intended for that purpose, but, on the contrary, are used in connection with metal weights inserted at some other point in the head of the club. The metal weight forming 75 part of my invention, as above described, constitutes the weight which it is necessary to add to the wooden head of the club, such weight being disposed where it contributes 80 the maximum of momentum during the swing of the club and being so proportioned as to secure perfect balance thereof.

In the drawings:

Figure 1 is a view in elevation of the head 85 of my improved club looking toward the striking face.

Figure 2 is a view of the underside of the head of the club, and

Figure 3 is a section through the head of the club in a plane transverse of the handle. 90

My invention may be applied to any wooden club such as a brassie or driver. The precise form of the metal weight may vary within considerable limits without departing from the conditions above set forth, 95 the principal requisites being, as above stated, that the weight be located at the extreme lower part of the club and that it be so proportioned as to secure the balance above referred to. As illustrated, the metal 100 insert 1 is shown as a flat plate of metal, preferably brass, set into the lower surface of the head of the club. The metal plate preferably extends from the front to the rear of the head of the club, the forward 105 edge 2 thereof being flush with the front face of the club and forming the lower part thereof. At its rear edge, as indicated at 3, the metal plate may be tapered to conform to the curvature of the rear side of the club, 110 and it may be similarly tapered at the points designated 4 and 4' in such manner that the

curved lower surface of the metal plate will merge into the curved lower surface of the head of the club. By reason of the amount of metal in the weight the forward edge 2 thereof is of sufficient thickness to form all of the reinforcement and protection necessary at the lower part of the front face of the club, thus preventing injury to the club from gravel or other hard objects with which it may contact and dispensing with the necessity of the usual insert of fiber or other material.

By reason of the fact that the normal and proper point of contact between the striking face of the club and the ball is at some distance above the forward edge 2 of the metal weight there will be a tendency for the weight to shift forwardly upon impact of the club with the ball. This tendency of the weight to shift is due, of course, to the fact that the momentum of the part of the club above the weight is partially arrested by contact with the ball while the momentum of the weight is undiminished. In using clubs such as herein described I have found that the undiminished momentum of the weight imposes a severe strain upon the screws and I have therefore constructed the weight with vertical, or substantially vertical shoulders projecting into the upper part of the head of the club for the purpose of absorbing the shock referred to. By employing such shoulders the screws are almost wholly relieved of horizontal strains, such strains being absorbed by the shoulders. These shoulders for absorbing the horizontal momentum strains may, of course, take a wide variety of forms and may be placed in a variety of positions upon the upper surface of the metal weight, it being necessary merely that the shoulders extend transversely of the plane of contact between the upper surface of the metal weight and the lower surface of the wooden part of the club, i. e., transverse of the arc through which the head of a club moves when the ball is struck. In the drawings, I have shown two such shoulders 6 and 7. These shoulders 6 and 7 form the forward surfaces of lugs projecting upward from and integral with the metal weight. The part of these lugs rearwardly from the forward vertical shoulders may slope rearwardly, as indicated at 9 and 10. When so constructed the parts of the head of the club may conveniently be assembled by recessing the under-surface of the club to receive the weight and then placing the weight against the under-side of the club in correct position, whereupon the application of slight pressure or a hammer blow will indent the edges of the lugs into the lower surface of the wooden part of the club sufficiently to mark the position of the cavities to be cut therein to receive the lugs. These cavities or recesses

may then be chiseled out, it being necessary to cut these cavities accurately only on their vertical forward sides where they coact with the shoulders 6 and 7. After the cavities are made the weight can be replaced, driven forward so as to secure firm contact between the shoulders 6 and 7 and the forward walls of the cavities whereupon insertion of the screws will complete the proper assembly of the device, the forward edge 2 of the plate being dressed down, if necessary, after assembly, to make it flush with the remainder of the striking face of the club.

Another advantage inherent in the use of a club weighted as described and claimed herein lies in the fact that the head of the club instead of being weakened by the weight is made stronger and more resistant to shocks and wear. This is true not only as regards the striking face of the club, but also of the rear part of the club. Golf clubs are commonly worn down in use at the point designated in the drawing by the reference numeral 3, and it frequently happens with clubs having weights inserted in the rear of the head that the wood beneath the inserted weight is shattered, this being especially likely to happen when the weight is placed low, as desired by some players, the low portion of the weight leaving only a thin and fragile shell of wood between the weight and lower surface of the club. My invention avoids this difficulty altogether, and serves to add strength and resistance to wear to the club at the point 3.

The metal weight 1 is secured in position by means of screws 5 which, in themselves, contribute to the weight of the club at the desired point. I have shown the weight as tapering in horizontal section from the front to the rear edge, this shape conforming to the usual contour of the head of the club, and, furthermore, resulting in properly distributing the weight to secure the desired balance of a club having a head of the form illustrated. Upon reference to Figure 2 it will be observed that the part of the weight above the central plane 6-6, while shorter in a direction perpendicular to the central plane, is wider, thereby resulting in approximately the same mass of metal being disposed upon opposite sides of the central plane. By this arrangement of the weight the club normally tends to assume the proper position for striking, a fact which can be easily observed by lightly holding a club constructed in accordance with my invention. It will be obvious that with club heads projecting more or less forwardly or rearwardly from the plane of the shaft the form of the weight would be varied accordingly to keep the center of gravity of the head in a plane passing through the axis of the shaft and approximately perpendicular to the sole, thereby obtaining the

balance above referred to. It will be apparent that, owing to the variety of shapes of the heads of clubs, it will not in all instances be necessary, or perhaps desirable, 5 that the center of gravity be in a plane precisely perpendicular to the sole, it being sufficient that the center of gravity be near enough to such a plane to obtain the desired balance.

10 While I have described the application of my invention to a wooden club, it can be applied with equal advantage to clubs made of other relatively light material such as indurated fibre, aluminum or other material 15 of such light weight as to render the use of added weight desirable.

A weight constructed and applied to a golf club according to my invention offers a further advantage in the facility with 20 which the weight and balance of the head of the club may be altered, it being necessary only to unscrew the weight, remove it from the club and to remove metal by drilling or otherwise from the upper surface of 25 the weight at the desired points. Added weight may be applied to the club at any point by drilling holes in the head above the upper surface of the weight and filling the same with metal. When the weight is 30 again secured in position the alterations are concealed from view, thus rendering it possible to make the desired adjustment without injuring or altering the appearance of the club in any manner.

35 The application of weight to the head of a golf club according to my invention is conducive to imparting movement in the correct direction to the ball. When the weight added to the head of a golf club is concentrated within a small compass with the principal mass thereof above the sole, as when lead weights are inserted in the rear side of 40 the head of the club, it is necessary that in making a stroke the striking face of the club 45 contact with the ball opposite the weight. If the point of contact between the striking face of the club and the ball be at either side of the ideal striking point, that is, toward the heel or toe of the club and not opposite the weight, the ball will be driven to one 50 side or the other of its intended course. This difficulty is to a great extent mitigated by placing the weight at the sole and distributing the added weight between the heel 55 and toe of the club, as is the case with clubs constructed according to my invention. In using my improved club a moderate deviation of the point of contact of the club with the ball from the center of the striking face 60 does not throw the point of contact out of line with the weight to as great an extent as when the weight is concentrated within a small compass, and the weight, by reason of being at the extreme end of the club, acts 65 with a mechanical advantage over the resist-

ance offered by the ball which contacts with the club at an appreciable distance above the sole.

While I have herein described a particular embodiment of my invention, it will 70 be apparent that the principles of construction as to disposition of the weight to secure maximum of momentum and a proper balance of the club may be secured without adhering to the precise form of construction 75 herein illustrated and described.

What I claim is:

1. A golf club having a head consisting of an upper section of wood and a lower section of metal, said metal section containing sufficient metal to impart the desired weight to said head and being secured to the lower surface of the wooden section with its forward edge flush with and forming the lower reinforced part of the striking face, 80 and its lower surface forming the sole of the club, said sole extending only over the central portion of the lower surface of the wooden section, terminating at a considerable distance from the toe of the head on one side and at a considerable distance from the heel of the head on the other side, said metal and wooden sections having coacting shoulders extending transversely to their contacting surfaces, said shoulders being positioned to exert a maximum resistance to 85 the tendency of the metal section to fly off when the club strikes the ball with its striking face.

2. A golf club having a head consisting 100 of an upper section of wood and a lower section of metal, said metal section containing sufficient metal to impart the desired weight to said head and being secured to the lower surface of the wooden section with 105 its forward edge flush with and forming the lower reinforced part of the striking face, and its lower surface forming the sole of the club, said sole extending only over the central portion of the lower surface of the 110 wooden section, terminating at a considerable distance from the toe of the head on one side and at a considerable distance from the heel of the head on the other side, the center of gravity of said metal section being 115 so disposed as to bring the center of gravity of said head in a plane passing through the axis of the shaft of the club and substantially perpendicular to the sole of the club, said metal and wooden sections having co- 120 acting shoulders extending transversely to their contacting surfaces, said shoulders being positioned to exert a maximum resistance to the tendency of the metal section to fly off when the club strikes the ball with 125 its striking face.

3. A golf club having a head consisting of an upper section of relatively light material and a lower section of metal, said metal section containing sufficient metal to impart the 130

desired weight to said head and being secured to the lower surface of the lighter section with its forward edge flush with and forming the lower reinforced part of the 5 striking face, and its lower surface forming the sole of the club, said sole extending only over the central portion of the lower surface of the wooden section, terminating at a considerable distance from the toe of the head 10 on one side and at a considerable distance from the heel of the head on the other side, said metal and lighter sections having co-acting shoulders extending transversely to their contacting surfaces, said shoulders being positioned to exert a maximum resistance to the tendency of the metal section to 15 fly off when the club strikes the ball with its striking face.

4. A golf club having a head consisting 20 of an upper section of relatively light material and a lower section of metal, said metal section containing sufficient metal to impart the desired weight to said head and being secured to the lower surface of the lighter

section with its forward edge flush with and 25 forming the lower reinforced part of the striking face, and its lower surface forming the sole of the club, said sole extending only over the central portion of the lower surface of the wooden section, terminating at a considerable distance from the toe of the head on one side and at a considerable distance 30 from the heel of the head on the other side, the center of gravity of said metal section being so disposed as to bring the center of gravity of said head in a plane passing through the axis of the shaft of the club and substantially perpendicular to the sole of the club, said metal and wooden sections having coacting shoulders extending trans- 35 versely to their contacting surfaces, said shoulders being positioned to exert a maximum resistance to the tendency of the metal section to fly off when the club strikes the ball with its striking face.

In testimony whereof, I have subscribed my name.

HUGH MOODY RHIND.
